TOY GUN CONSTRUCTION

Robert L. Wehrfritz, New Brunswick, N. J.
Application May 8, 1956, Serial No. 583,536

6 Claims. (Cl. 124—27)

The present invention relates to an improved construction of a toy gun of the type in which a simulated bullet or like missile is propelled from the gun barrel by means of a propulsion spring.

It is an object of the invention to provide a new and improved toy gun of such simple construction as to be comprised in its entirety by only five principal parts including a simulated projectile.

It is a further object of the invention to provide a novel toy gun of sturdy and reliable construction particularly suited to large-scale low-cost mass production, and one which may easily and readily be miniaturized without change of construction for use in the field of novelty jewelry.

Other objects and advantages of the invention will appear as the detailed description proceeds in the light of the drawing forming a part of this application and in which:

Fig. 1 illustrates in top plan view, and Fig. 2 in elevational cross-sectional view, a toy gun embodying the present invention; and

Figs. 3 and 4 are cross-sectional elevational views illustrating certain phases of operation of the toy gun herein disclosed.

Referring more particularly to Figs. 1 and 2, the present invention is here illustrated as embodied in a toy gun of a form suitable for use as novelty jewelry. The gun includes mutually mating half-portion gun members 10 and 11, which may conveniently be formed as metal castings, secured together as a unitary structure by one or more machine screws or rivets 12 to provide a hollow gun barrel 13 and integral stock 14. The gun further includes a unitary simulated hammer and trigger member 15, formed as a sheet metal stamping or metal casting, pivotally supported by a pin 16 within a transverse slot 17 provided in the gun portions 10 and 11 at the rear end of the barrel 13. The pivot pin 16 may either be a machine screw which also aids in maintaining the mating half-portions 10 and 11 in assembled relation or may be a pin integrally die cast or otherwise integrally formed with one of the mating half-sections 10 or 11.

The member 15 includes a simulated hammer spur 18 and a finger trigger 19, and is provided with a hammer projection 20 in alignment with and extending longitudinally down the barrel 13 but forming a significant angle to the axis of the latter. An elongated, helical, projectile-propulsion spring 21 is positioned within the barrel 13 with one end of the spring extending over the hammer projection 20 which has a width sufficiently large as positively to retain the spring in position within the barrel. The projection 20, angled with respect to the axis of the barrel 13, bends the rear end of the spring 21 out of axial alignment with the remainder of the spring to derive a spring bias force which tends to maintain the hammer always in cocked position even in the absence of a compressive force exerted longitudinally on the spring. The member 15 also includes an integrally formed latch-dog 22, which may be shaped to simulate a barrel supporting

portion of the stock 14, having a latch element 23 positioned at its forward end to extend through a longitudinal blind slot 24 provided on the underside of the barrel 13. With the simulated hammer member in cocked position, the latch element 23 is positioned in latching engagement with the mushroom shaped head 25 of a simulated projectile 26 loaded in the barrel 13 in readiness to be fired. The latch element 23 and mushroom head 25 are provided with a sharp cooperating rake angle as illustrated to provide positive latching action sufficient to prevent manual extraction of the projectile 26 from the gun barrel once the projectile has been latched therein.

A toy gun embodying the present invention is quite well suited for use in the field of novelty jewelry as earlier mentioned, and for this application the simulated projectile 26 may be tethered to the toy gun by a small chain 27 as illustrated more clearly in Fig. 3. Thus the projectile may be provided with an eye 28 at its forward end to receive a link 29 at one end of the chain, and the other end of the chain is secured in a machine screw eye 30 or the like suitably affixed to the underside of the barrel 13 near its forward end.

The projectile 26 is loaded by manually inserting it within the gun barrel 13 and forcing it down the barrel against the compressive force of the spring 21 until the mushroom head 25 of the projectile is engaged and latched by the latch-dog 22. This compresses the spring 21 between the hammer-trigger member 15 and the head 25 of the projectile, and the compressed spring 21 now propels the projectile from the gun upon manual pressure placed upon the trigger 19 to withdraw the latch-dog 22 from engagement with the head 25 of the projectile as shown in Fig. 3. It will be noted that the hammer projection 20 has moved to a position where it clamps the rear end of the spring 21 against the inner surface of the barrel 13 as the projectile moves out of engagement with the spring 21. Thus the momentum imparted to the forward length of the spring by virtue of its expanding action is not able to pull the spring out of the barrel, as would otherwise occur were the rear end of the spring not retained by the hammer projection 20. Upon manual release of the trigger 19, the rear end of the spring being bent out of alignment with the axis of the spring by virtue of the angled relation of the hammer projection 20 biases the hammer-trigger member 15 to cocked position. As the member 15 is so moved toward cocked position, the latch element 23 re-enters the barrel 13 and in doing so moves into latching engagement with a turn of the spring 21 so that the latter is retained in position within the barrel not only by the latch-dog 22 but also by the hammer projection 20 as illustrated in Fig. 4. The spring 21 is accordingly always positively retained within the gun barrel without the need for using a spring retaining pin or locking web or diaphragm extending across the interior of the barrel or otherwise affixing the spring to the hammer member 15 as has heretofore been required in prior toy gun constructions. At the same time, it will be evident that the full length of the spring 21 is essentially available to exert a propulsive force on the simulated projectile.

It will be apparent from the foregoing description of the invention that a toy gun embodying the invention is of exceptionally simple construction involving a minimum number of components, and that its construction is both sturdy and suitable for large-scale low-cost mass production adaptable both for the toy field and the field of novelty jewelry.

What is claimed is:

1. A toy gun comprising, mutually mating half-portion members secured together as a unitary structure providing a hollow gun barrel and integral stock, a unitary simulated hammer and trigger member pivotally posi-

tioned in said unitary structure at the stock end of said barrel and including a hammer projection enclosed within said structure to extend longitudinally along said barrel and forming an angle with respect to the axis thereof, an elongated helical projectile-propulsion spring positioned within said barrel with one end of said spring extending over and retained by said hammer projection, said angle of said projection bending said spring out of alignment to derive a spring biasing force tending to maintain said hammer in cocked position even in the absence of a compressive force longitudinally of said spring, and a latch actuated by said member for releasably latching a projectile inserted into position in said barrel against the longitudinal compressive force of said spring.

2. A toy gun comprising, mutually mating half-portion members secured together as a unitary structure providing a hollow gun barrel and integral stock having a transverse slot extending therethrough at the rear end of said barrel, a unitary simulated hammer and trigger member pivotally secured in said transverse slot and including an integrally formed hammer projection enclosed within said structure to extend longitudinally along said barrel and forming an angle with respect to the axis thereof, an elongated helical projectile-propulsion spring positioned within said barrel with one end of said spring extending over and retained by said hammer projection, said angle of said projection bending said spring out of alignment to derive a spring biasing force tending to maintain said hammer in cocked position even in the absence of a compressive force longitudinally of said spring, and a latch actuated by said member for releasably latching a projectile inserted into position in said barrel against the longitudinal compressive force of said spring.

3. A toy gun comprising, mutually mating half-portion members secured together as a unitary structure providing a hollow gun barrel and integral stock, said gun barrel having a latch aperture intermediate its length to receive a latch element, a unitary simulated hammer and trigger member pivotally positioned in said unitary structure at the stock end of said barrel and including an integral hammer projection enclosed within said structure to extend longitudinally along said barrel and forming an angle with respect to the axis thereof and further including an integral latch-dog extending along and exteriorly of said barrel with a latch element positioned in said barrel aperture and movable into latching engagement with the grooved head of a projectile inserted in said barrel, and an elongated helical projectile-propulsion spring positioned within said barrel with one end of said spring extending over and retained by said hammer projection, said angle of said projection bending said spring out of alignment to derive a spring biasing force tending to maintain said hammer in cocked position even in the absence of a compressive force longitudinally of said spring.

4. A toy gun comprising: mutually mating half-portion body members secured together as a unitary structure providing a hollow gun barrel, a gun stock, and a gun-lock chamber rearwardly of said barrel; a metal

member having the configuration of a simulated hammer portion including a downwardly and forwardly projecting lug at the general position of a rim-fire percussion impacting element thereof, a trigger portion, and a latch-dog portion; a pivot pin pivotally supporting said metal member in said gun-lock chamber with said lug above said pivot pin and aligned with the bore of said barrel and said latch-dog generally aligned with said pivot pin and extending along the underside of said barrel as a simulated elongated support thereof; and an elongated helical projectile-propulsion spring slidably positioned within said bore of said barrel with the rear end of said spring extending over, anchored by, and bent out of alignment by said hammer lug and providing an ever present bias force tending to move said simulated hammer portion to cocked position; said latch-dog including at its forward end a latch element extending through a cooperating blind aperture in the underside of said barrel into latchable engagement with a projectile in firing position in said barrel.

5. A toy gun in accordance with claim 4 which includes a projectile tethered to said gun and including a convex mushroom-shaped head engageable with the open end of said spring and providing a circumferential latching groove having an acute rake angle cooperating with a corresponding acute-rake-angle surface provided on said latch element for positive latch-lock engagement.

6. A toy gun comprising a structure providing a hollow gun barrel and integral stock, a unitary simulated hammer and trigger member pivotally positioned in said structure at the stock end of said barrel and including an integral hammer projection enclosed within said structure to extend longitudinally along said barrel and forming an angle with respect to the axis thereof and further including an integral latch-dog extending along said barrel with a latch element thereon movable with said member to projectile-engaging position within said barrel and projectile-disengaging position, and an elongated helical projectile-propulsion spring positioned within said barrel with one end of said spring extending over and retained by said hammer projection, said angle of said projection bending said spring out of alignment to derive a spring biasing force tending to maintain said hammer in cocked position even in the absence of a compressive force longitudinally of said spring and said projection and latch element respectively locking and latching said spring within said barrel alternately with movement of said latch element to said projectile-engaging and disengaging positions thereof.
